UNITED STATES PATENT OFFICE.

MAURICE GASTON OLIVIER, OF PARIS, FRANCE, ASSIGNOR TO SOCIÉTÉ
FRANÇAISE DE LA VISCOSE, OF PARIS, FRANCE.

SELF-FIXING PROTECTIVE COVERING FOR BOTTLES, JARS, OR OTHER VESSELS.

No. 823,355.

Specification of Letters Patent.

Patented June 12, 1906.

Application filed February 1, 1906. Serial No. 299,039.

To all whom it may concern:

Be it known that I, MAURICE GASTON OLIVIER, engineer, a citizen of the French Republic, residing at Paris, France, have invented certain new and useful Improvements in Self-Fixing Protective Coverings for Bottles, Jars, or other Vessels, of which the following is a specification.

Bottles containing liquid or other preparations are usually closed with a stopper or cork and also generally provided with a protective covering, which may be of leather, skin, metal, paper, or other suitable material, for the fixing of which certain manual or mechanical operations are necessary.

I have found that a film of cellulose, such as can be obtained by precipitation from the solution of cellulose known as "viscose," can be prepared into suitable shape or form, and this when placed upon the bottle, jar, or other vessel shrinks by loss of moisture and attaches itself spontaneously at all points of possible contact, forming a perfectly tight joint. Thus for an ordinary stoppered bottle used to put up pharmaceutical preparations I cast or mold these coverings of cellulose hydrate by coating the rounded and closed ends of cylindrical tubes with viscose and setting the solution by any of the well-known means. The shaped films are detached, purified and washed, and preserved in contact with water in the hydrate condition. These films are made slightly larger than the neck of the bottle or vessel to be covered, so that they slip on quite easily. The length is also adjusted according to requirements. The film when placed on the bottle or vessel shrinks spontaneously and readily accommodates itself to the shape of the vessel. Solutions of cellulose other than viscose having similar properties may of course be used.

The essence of my invention consists in the fact that the cellulose film in its hydrated form shrinks very considerably as it parts automatically with its moisture, that during its spontaneous shrinkage it takes the form of, and molds itself upon, the stopper or cork on which it is placed, making a perfectly

tight joint, and that in the air-dry state it possesses the tensile properties necessary to withstand the strains which are set up by the shrinkage. The joint above referred to is so perfect that there is not the slightest leakage with fatty matters or the most mobile liquid, like petroleum.

In the drawing the figure illustrates in broken elevation a bottle having my improved covering applied thereto.

In said drawing, 1 indicates the body of the bottle; 2, the neck thereof; 3, the cork inserted in said neck, and 4 my improved coating or covering applied about the neck of the bottle and over the top of said cork.

I claim—

1. A self-fixing protective covering for bottles, jars, or other vessels, comprising an appropriately-shaped film or covering of cellulose hydrate adapted, when placed upon the bottle or other vessel, to shrink by loss of moisture and so attach itself firmly at all points of possible contact, substantially as hereinbefore described. 65

2. The method of producing a self-fixing protective covering for bottles, jars or other vessels, which consists in forming a body of cellulose hydrate into the shape of the covering desired, but slightly larger than the neck of the bottle or vessel to be covered, so that upon application to the bottle it will shrink by loss of moisture and attach itself firmly at all points of possible contact. 75

3. The method of producing a self-fixing protective covering for bottles, jars or other vessels, which consists in precipitating cellulose hydrate from the solution of cellulose known as viscose, and then shaping the cellulose into the form of a cap or covering of a size slightly larger than the neck of the bottle or vessel to be covered. 85

In testimony whereof I have hereunto set my hand in presence of two subscribing witnesses.

MAURICE GASTON OLIVIER.
